1940. The following table gives the results of the 1940 Census of
Population and the 1930 Census of Population for the 1940
Census Bureau's 1940 Standard Metropolitan Statistical Areas.
The 1940 Census Bureau's definition of a Standard
Metropolitan Statistical Area is as follows: "A Standard
Metropolitan Statistical Area is a county or group of
counties which contain a central city of 50,000 or more
population, and which have a high degree of social and
economic integration with the central city, as measured by
the density of population within a 50-mile radius of the
central city, the economic relationship between the central
city and the surrounding area, and the amount of
intercity commuting between the central city and the
surrounding area." The 1940 Census Bureau's definition
of a Standard Metropolitan Statistical Area is as follows:

THERMOSTATICALLY CONTROLLED HEATING SYSTEM FOR TOBACCO BARNS AND THE LIKE

George Wiley Harding, Lynchburg, Va., assignor to Automatic Draft and Stove Co., Inc., Lynchburg, Va.

Application May 6, 1946, Serial No. 667,610

1

This invention relates to thermostatically controlled heating systems for barns and the like, and particularly tobacco barns employing the flue cure method.

It is common practice in tobacco barns to have a furnace on the outside of the structure connected to flues extending through the barn so as to heat the structure during the curing season. The tobacco is placed on racks and spaced so air can circulate through the tobacco, but unless an even temperature is maintained imperfectly cured tobacco results. Wood as a fuel is most readily available, but heretofore has been objectionable in that it is very difficult to maintain the fire without frequent refueling and resulting differential in temperature. Where wood is the fuel no grate is used, the air being drawn by the flues through the wood.

In my investigation I have found that the heating unit using wood must be airtight so that the combustion will be controlled through the inlet. In the curing of tobacco it is essential that not only an even temperature be maintained, but a fairly high temperature. Where the temperature in the draft is manually operated, it is virtually impossible to maintain an even temperature, and this is aggravated by the unnecessary combustion of fuel due to the draft being left open beyond the required period.

I have further found that it is highly desirable to have preheated air slowly fed to the fuel. By having an airtight combustion chamber, a downdraft pipe entering the combustion chamber with a thermostatically controlled damper in the downdraft pipe, the thermostat responsive to the needs of the barn, I obtain highly successful results.

Of necessity, the thermostat cannot be expensive and is devoid of the fine adjustment present in an expensive instrument. The use of the downdraft pipe serves as a reservoir of pre-heated air under operating conditions, which slowly feeds air into the combustion chamber, giving the fire every chance to absorb the air or oxygen, thus bringing the wood char into a glow or flame, and at the same time retaining the heated air within the combustion chamber so as to permit the extraction of maximum heat units from the fuel before passing into the flues.

The downdraft pipe might be compared to a shock absorber in its action. The hot air in the downdraft has a tendency to rise, but upon the opening of the damper in the downdraft stack, a draft is created at the chimney serving to draw the air in the downdraft stack into the com-

(Cl. 237—2)

bustion chamber. It must, however, overcom

5 the tendency of the heated air to rise, and thus there is no rush of air which might be detrimental to combustion at a low state, the pre-heated air being fed slowly into the combustion chamber against the fuel. Should the thermostat open the damper too wide, the reservoir of air in the downdraft stack compensates this factor by having available an accumulated supply of 10 stored air which answers the needs of the stove without a sudden inrush of air which might be detrimental at a low stage of combustion. It is essential that such a heating unit operate at a low temperature and maintain combustion. Fuel 15 under this condition is really warm charcoal or wood char. At the low combustion temperatures, the downdraft stack or column of preheated air contributes most to the effective operation of the thermostat. The air in the downdraft stack is

20 heated and tends to move upwardly and the effective chimney is relatively short since the draft is caused by the ascension of warm air. The effective height of any chimney is the height to

25 effective height of any chimney is the height which a solid column of warm air extends; hence the effective chimney height depends upon the condition of the fire in the combustion chamber.

Thus at low temperatures in the heating unit the compensating flue of the downdraft stack is high since the column in the chimney is short and that in the downdraft warmer. With a

and that in the nearly balanced condition the downdraft of air which occurs in the downdraft stack is necessarily very slow. It is little more than a drift during the early stage of combustion. The slow

35 during the early stage of combustion. The slow diffusion of warm air over the warm charcoal creates a slow air current conducting heat of oxidation to adjacent charcoal. The ideal condi-

tion for bringing up a fire from sub-incandescent temperature is for the air current to increase infinitesimals in step with temperature rise and amount of charcoal heat. Thus the preheated

amount of charcoal heat. Thus the position of the column of air definitely affects the operation of the thermostat so that the feeding of the air onto the charcoal for operation of the damper is gradual.

45 uated and refined far beyond the normal operation of the thermostat on the valve or damper located in conjunction with an opening at the bottom of the heating unit without such a down-

50 A thermostat operating a flap valve not attached to a downdraft stack would not have the

tached to a downblast stack would not have a compensating factor of rising air with resulting slow feed or drift into the combustion chamber. A tendency for the air to rise in the flue or exit duct would be ruled. The velocity of air may

ing over the warm charcoal will be increased the closer the air inlet is to the charcoal. If the air is diffused slowly to the warm charcoal, the temperature would climb because infinitesimal heat units would be subtracted from the charcoal, whereas if it is blown directly across the warm charcoal it would probably be cooled faster than oxidation could occur.

In a coal burning stove there is a grate on which ashes accumulate, and unless removed from it form an insulating layer on which rests closely nested coal. Below the grate bars is an air chamber in the form of an ash pit. Air usually enters through the ash door, and in order to reach the fire is drawn through the grate bars, ashes and fuel. This requires a strong draft, and the placing of a downdraft on the outside of the heater entering the ash pit will only serve to further slow down and impede the air flow, so that an entirely different problem is presented where wood is the fuel.

The principal object of my invention is to provide an airtight wood burning heating unit for tobacco barns and the like having a downdraft thermostatically controlled so located and adjusted as to result in the most efficient curing of tobacco.

Another object is to provide an attachment for flue equipped tobacco barns designed for burning wood comprising a downdraft having a temperature thermostatically controlled from within the barn and adjacent to the tobacco.

Other objects will be disclosed in the specification and claims forming a part of this application.

In the drawings:

Figure 1 is a fragmentary vertical section of the heating unit in elevation;

Figure 2 is a fragmentary front elevation of the heating unit;

Figure 3 is an enlarged detail of the downdraft and thermostat connecting mechanism; and

Figure 4 is a bottom plan view of the U-shaped member connecting the counter-balance and thermostat.

Figure 5 is a horizontal section through a tobacco barn illustrating conventional duct arrangement.

Referring to the drawings, in which similar parts are designated by like numerals:

Numeral 5 designates an airtight brick oven or heating unit which could be of any airtight construction extending from the outside into the structure to be heated, and having a fuel door 6 with a downdraft stack 7 extending from outside of the building into the combustion chamber 8. Extending from the rear of the heating unit 5 are a plurality of flues 9 which extend around the walls of the barn and, if desired, through the tobacco, coming together in a single flue 10.

Inside the downdraft stack 7 is a pivotal damper 11 connected to an arm 12 exterior of the stack, which in turn is connected by a chain 13 to a bell crank 14 pivoted to a support 15 and having a counterweight 16. A U-shaped channel member 17, shown in detail in Figure 4, having a plurality of adjustment holes 18 is connected by a pin 19 to a projecting toe 20 forming a part of the lever 14. A wire or rod 21 is welded or otherwise secured to the U-shaped channel member 17 and is connected at its other end to a bi-metal thermostat 22. A support 23 extends inside of the barn or other structure having a platform 24 on which the fulcrum support 15 rests and an arm 25 extending from the support 75

23 having the bi-metal thermostat 22 at its outer end, the arm 25 being braced by wires 26 with turn-buckles 27 to adjust the wires. The arm 25 extends into the structure a sufficient distance and at a height to maintain the barn at a proper temperature and make the thermostat responsive to the desired temperature.

I have found that location of the thermostat approximately six feet from the floor gives the best results. A thermostatic bi-metal dial thermometer 28, with the thermometer on the inside of the building and the dial on the outside adjacent the heating unit, serves to make available to the operator the temperature within the structure. A cap 29 is positioned over the downdraft stack, and a manually operated damper 30 is placed near the outer end of the down stack 7 to supplement the thermostat when desired. Tiers of tobacco 31 are arranged throughout the barn in the usual manner.

As illustrated, the thermostat control downdraft stack, damper, support, thermostat, and bell crank lever with connecting mechanism can be installed as a unit where the barn is already equipped with the heating unit and flues, or it can take the form of a complete heating unit, including the airtight heating unit and flues added to accommodate the size of the building. Obviously the size of the heating unit will depend upon the 30 cubic contents of the building to be heated and its heating capacity will increase in proportion to the size of the structure.

As actually used, the damper 11 will be normally open and the responsiveness of the thermostat 22 adjusted through the holes 18 in the U-shaped member 17 by placing the pin 19 in the desired opening, thus controlling the movement of bell crank 14. The counterweight 16 will serve to offset the weight of the arm 14, the chain 13 and the damper 11, so that although the damper will be normally open, very little effort is required to close it. The expansion of the bi-metal thermostat 22 will serve to advance the wire 21, moving the toe 20 forward, lowering the arm 14, and in 45 turn the arm 12, resulting in the closing of the damper 11. Upon the interior of the barn cooling-off, the bi-metal thermostat 22 will contract, pulling on the wire 21 and through the various linkages serve to open the damper 11. The accumulated warm air in the downstack 7 serves to compensate for any inefficiency of the thermostat and results in an even heat being diffused through the barn, and a constantly maintained damper which is essential to properly cured tobacco. By inefficiency of the thermostat is meant course or sudden opening of the damper valve which attends the use of a cheap thermostat as contrasted with very gradual opening of the damper valve when controlled by a more expensive thermostat. Even though the damper valve may open wide and suddenly, there will be no sudden rush of air into the combustion chamber, due to the counterbalancing effect of the column of warm air in the down draft stack on the head of heated combustion products in the discharge flue. The wood fuel is placed in the heating unit through the fuel door 6, the fire box 8 being big enough to receive large pieces of wood. The automatic regulation of the damper maintaining the temperature at a constant level in the building, along with the downstack operation, serves to conserve fuel and make a most efficient and economical operation. The ducts 9 convey the heat directly from the fire box throughout the barn converging into a single discharge flue, thus con-

veying the heat through the structure providing the maximum utilization of B. t. u.'s, portions of said ducts anterior to said discharge flue extending substantially horizontally.

Under this arrangement, maximum heat efficiency is obtained. The downdraft stack on the exterior of the structure and the ducts within the building may be likened to counterbalancers. As the warm air in the duct increases it will overcome the tendency of the warm air in the downdraft stack to rise and will draw it into the combustion chamber with increasing velocity until the desired temperature is reached, thus operating the thermostat, and in turn the damper in the downdraft stack. Under this arrangement, the smoke will ultimately find its way out through the flue but most of the B. t. u.'s will be expended within the structure. As the fire dies down, the warm air in the downdraft stack will build up and that in the ducts decrease. Upon the opening of the damper, due to thermostatic action, the preheated air in the downdraft stack will gradually flow into the combustion chamber, and as the fire builds up, the warm air in the ducts will increase, increasing the rate of flow from the downdraft stack which is desirable after the low temperature phase has passed. Instead of a fluctuating heat which burns fiercely at one phase overheating the structure and quickly dying down, you have a short cycle of combustion with the damper open and a long off-cycle resulting in economy and even heat. The downdraft stack with the damper thermostatically controlled positioned on the outside of the structure at one end and the combustion chamber with the ducts extending from the other end, finally terminating in the flue, contributes largely to these results.

Various modifications in the construction and arrangement of parts will readily suggest themselves to those skilled in the art, but within the scope of the present invention as claimed.

What I claim is:

1. A heating system for tobacco barns comprising an enclosure to be heated, a wood burning heater including a combustion chamber having a down draft stack at its forward end outside said enclosure, and a combustion products duct

extending from its rear end within said enclosure, said duct terminating in an up draft flue discharging outside said enclosure at a height above said down draft stack, the major portion of said duct between said heater and up draft flue being substantially horizontal and in heat exchange relation to the air within said enclosure, a damper in the upper part of said down draft stack, a thermostat mounted within said enclosure at a remote point from the walls thereof, and operating connections from said thermostat to said damper.

15 2. A heating system for tobacco barns comprising an enclosure to be heated, a wood burning heater including a combustion chamber having a down draft stack at its forward end outside said enclosure and a combustion products duct extending from its rear end within said enclosure, said duct terminating in an up draft flue discharging outside said enclosure at a height above said down draft stack, the major portion of said duct between said heater and up draft flue being substantially horizontal and in heat exchange relation to the air within said enclosure, a damper in the upper part of said down draft stack, a thermostat mounted within said enclosure, a support for said thermostat, an arm extending from said support to a point remote from the walls of said enclosure, said thermostat being positioned at the end of said arm, a bell crank carried by said support, adjustable means connecting said bell crank and thermostat, means connected to said bell crank and said damper for operating said damper responsive to the thermostat.
